Specification for Design.

Patented Mar. 23, 1920.

Application filed November 25, 1919. Serial No. 340,683. Term of patent 14 years.

To all whom it may concern:

Be it known that I, DAVID ADNA BROWN, a citizen of the United States, residing in Philadelphia, in the county of Philadelphia and State of Pennsylvania, have invented a new, original, and ornamental Design for a Badge, Emblem, or Similar Article, of which the following is a specification, reference being had to the accompanying drawing, forming a part thereof.

The figure of the drawing is a plan view of a badge, emblem or similar article, showing my new design.

I claim:

The ornamental design for a badge, emblem, or similar article as shown.

In testimony whereof I have hereunto signed my name this 20th day of November, A. D., 1919.

DAVID ADNA BROWN.
